UNITED STATES PATENT OFFICE.

CHARLES J. YASENSKY, OF WEYBURN, SASKATCHEWAN, CANADA.

COMBINED AEROPLANE AND BALLOON.

1,279,068.

Specification of Letters Patent. Patented Sept. 17, 1918.

Application filed August 27, 1917. Serial No. 188,511.

To all whom it may concern:

Be it known that I, CHARLES J. YASENSKY, a British subject, residing at Weyburn, Province of Saskatchewan, Dominion of Canada, have invented certain new and useful Improvements in Combined Aeroplanes and Balloons, of which the following is a specification.

The primary object of the invention is 10 the provision of a balloon provided with propelling mechanism as well as steering devices whereby the same may be employed for air navigation.

A further object of the device is the provision 15 of a balloon having a ready means for steering the same in its flight as well as for assisting in stabilizing the air craft, the device being of light weight and possessing great strength and durability.

20 A still further object of the invention is the provision of a navigating balloon having a readily controllable empennage arranged with adjustable movement guide connections with the fuselage, and operable at the will 25 of the aeronaut.

In the drawing forming a part of this application and in which like designating characters refer to corresponding parts throughout the several views,

30 Figure 1 is a side elevation of the device. Fig. 2 is a top plan view thereof.

Fig. 3 is a front elevation of the same.

Fig. 4 is a rear elevation of the invention.

Fig. 5 is an enlarged detail view of a portion 35 of the empennage and the mounting means therefor.

Fig. 6 is a side elevation of one of the steering cord manipulating members.

Fig. 7 is a front elevation of the said 40 member.

Fig. 8 is a view partially in elevation and partly in section of one of the adjustable universal joint sections for the empennage, and

45 Fig. 9 is an end elevation thereof with parts broken away.

It is designed to provide a balloon that is propelled by a motor and is readily steered through the air and the same is arranged 50 with a gas bag or balloon member 10 somewhat flattened and roughly representing the shape of a bird. The nose or bow 11 of the bag 10 is arranged with simultaneously operable bi-planes 12 arranged upon opposite 55 sides thereof and having a journaling axle 13 transversely arranged through the bow

portion 11 and provided with vertical arms 14 to the upper and lower ends of which operating cords 15 and 16 are attached. A car 17 is arranged below the bag 10 having 60 a motor driven propeller 18 at the rear end 19 thereof, the motor, not shown, being arranged within the car 17. A double winding drum 20 is also arranged within the car 17 having the cords 15 and 16 secured thereto 65 and wound upon the separated portions thereof in opposite directions while a turn crank 21 is provided for the drum. By turning the crank 21 so as to exert a pull upon the lower cord 16, the upper cord 15 70 is unwound from the drum 20 so that the arms 14 are moved for tilting the planes 12 forwardly and downwardly for permitting the air craft to dive, while a reverse movement of the drum 20 elevates the forward 75 sides of the planes 12 when it is desired to climb higher with the air craft.

The empennage 22 is carried by a rearwardly projecting rod 23 centrally attached to the tail or stern 24 of the bag 10 and 80 being cruciform in cross section so arranged as to provide opposite horizontal steering planes 25 arranged perpendicular to vertical steering planes 26. A ball and socket connection 27 is arranged as a mount for 85 the empennage 22 as well as a similar mount 28 whereby the empennage is carried by the stern rod 23. It will be understood that the said connections 27 and 28 are identical in form but are arranged at opposite angles, 90 whereby the connection 27 is releasable for permitting lateral movements of the empennage 22 while the connection 28 may be released for controlling the vertical shifting thereof. A ball member 29 is arranged 95 for one of the connections 27 and 28 while the socket member 30 thereof carries a spring pressed latch 31 adapted for moving in an arcuate slot or guide 32 in the ball 38 for seating within one of the recesses 33 in the ball when the empennage 22 is positioned at the desired adjustment.

A pull cord 34 is provided for each of the latches, 31, the said cords leading to the car 17 and whereby as will be evident upon 105 pulling the cord 34 of either of the connections 27 or 28, the empennage 22 will be free to turn in either a lateral or a vertical direction respectively. Cords 35 and 36 are attached to the upper and lower inner corner 110 respectively of the vertical plane 25 of the empennage 22 and have their forward ends

arranged within the car 17 and preferably provided with a drum operating means similar to the said drum 20 heretofore described in connection with the forward elevating planes. In a similar manner, cords 37 and 38 are attached to the rear outer corners of the horizontal plane 26 of the empennage 22 for shifting the latter laterally and having their forward ends similarly controlled within the car 17. From this detail description of the device, it will be understood that the bag 10 is maintained inflated at all times while the forward planes 12 as well as the horizontal planes 26 assist in maintaining the device horizontal while the empennage 22 is controlling for steering the device in any direction desired, the forward planes 12 being capable of controlling the upper and downward movements thereof when desired to do so. It will be understood that during the movements of the empennage 22, the same takes place when the required one of the latches 31 is released and that the inner end of said latch by moving within the groove 32 of the ball 29 of its respective ball and socket mounting connection is prevented from all movements excepting the desired vertical or horizontal steering movements. The balloon 10 maintains the craft in the air while its forward movement is insured by the motor driven propeller 18 and by means of the steering mechanism heretofore set forth the device may be employed for navigating the air in any direction as found desirable.

What I claim as new is:—

1. An air craft including a gas bag having a tail portion, a rearwardly projecting rod carried by said tail portion, a steering member comprising perpendicularly arranged planes, two universal joint supporting members connected between said steering member and said rod, one of said supporting members permitting swinging vertical movement and the other permitting swinging horizontal movement of said steering member, spring pressed retaining latches

carried by said supporting members adapted for retaining the latter in their adjusted positions, releasing means for said latches and operating cords attached to said steering member adapted for actuation when said latches are released.

2. An air craft comprising a gas bag having forward nose and rearward tail portions, simultaneously operable elevating bi-planes journaled upon said nose portion and arranged at opposite sides thereof, manually operated tilting means for said planes, a rearwardly projecting rod carried by said tail portion, a steering member comprising perpendicularly arranged planes, two universal joint supporting members connected between said steering member and said rod, one of said supporting members permitting swinging vertical movement and the other permitting swinging horizontal movement of the steering member, and means for latching each of said supporting members at different angular positions.

3. An air craft comprising a gas bag having forward nose and rearward tail portions, simultaneously operable elevating bi-planes journaled upon said nose portion and arranged at opposite sides thereof, manually operated tilting means for said planes, a rearwardly projecting rod carried by said tail portion, a steering member comprising perpendicularly arranged planes, two universal joint supporting members connected between said steering member and said rod, one of said supporting members permitting vertical swinging movement and the other permitting horizontal swinging movement of the said steering member, spring-pressed retaining latches carried by said supporting members adapted for retaining the latter in their adjusted positions, releasing means for said latches, and operating cords attached to said steering member adapted for actuation when said latches are released.

In testimony whereof I affix my signature.

CHARLES J. YASENSKY.
